Primary Examiner — Jasmine Mlinarcik(74) *Attorney, Agent, or Firm* — Kirton McConkie; Brian Tucker(57) **CLAIM**

The ornamental design for a modular interchangeable necktie, as shown and described.

DESCRIPTION

FIG. 1 is a front perspective view of a modular interchangeable necktie;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines depict portions of the modular interchangeable necktie that form no part of the claimed design.
